UNITED STATES PATENT OFFICE

JULIUS H. WEIN, OF SAN FRANCISCO, CALIFORNIA

NECKTIE STRETCHER

Application filed April 14, 1931. Serial No. 530,025.

The invention aims to provide a new and improved device for so stretching four-in-hand neckties as to remove wrinkles over-night, and with this end in view, a further aim is to provide a construction which is simple and inexpensive, yet efficient and desirable.

With the foregoing in view, the invention resides in the novel subject matter herein-after described and claimed, description being accomplished by reference to the accompanying drawings.

Fig. 1 is a perspective view.

Fig. 2 is an enlarged fragmentary elevation, partly in section.

Fig. 3 is a fragmentary elevation showing the relatively wide ends of the two sections of the stretching form.

Fig. 4 is an enlarged sectional view on line 20 4—4 of Fig. 2.

Fig. 5 is a perspective view of the clip with which the relatively wide ends of the form sections are slidably connected.

A preferred construction has been illus-trated and will be specifically described, with the understanding that within the scope of the invention as claimed, minor changes may be made.

A form 6 is provided for reception in a 30 four-in-hand tie to be stretched and smoothed, said form being flat and being composed of two longitudinally tapered sections 7 whose relatively narrow ends are connected with each other at 8. If more or less resilient ma-35 terial, for instance, celluloid, be used in con-structing the form, the narrow ends of the form sections 7 may be integrally connected with each other as shown, but otherwise may be hinged.

The inner corners of the relatively wide 40 ends of the form sections 7, are formed with notches 9 which receive the ends of a coiled compression spring 10, said spring exerting its force to spread said sections 7. This 45 spring and the wide ends of the form sections are received in a channel-shaped clip 11 which is preferably formed from a thin sheet metal plate, said clip being slidably connected with the form sections 7, by rivets or other fas-50 teners 12 which pass through openings 13

in the clip and through transverse slots 14 in said sections 7. The fasteners 12 and slots 14 limit the spreading movement of the form sections 7 under the influence of the spring 10 when the device is not in use and allow 55 said sections to be readily moved toward each other when inserting the device in a tie.

In forming the clip 11, I make use of a single plate, preferably of metal, said plate being folded upon itself and shaped to provide 60 a tubular bead 15 which receives the spring 10, and two parallel wings 16 which lie slidably against opposite sides of the form sections 7. The spring 10 is of a diameter con-siderably greater than the thickness of the 65 form sections 7 and hence projects laterally beyond opposite sides of said sections, as shown in Fig. 4, and due to housing of this spring in the tubular bead 11, it has no tend-ency to buckle inwardly between the inner 70 edges of said sections 7, but is smoothly guid-ed whenever it is compressed or expands.

In using the device, it is gripped in one hand and the two form sections 7 moved toward each other, thus transversely contract-ing the width of the form. In this contracted condition, the form is inserted into the four-in-hand tie to be stretched and smoothed, and as soon as the form is allowed to expand under the influence of the spring 10, the stretching 80 will take place. When the device is left in a tie for several hours, for instance, over-night, all wrinkles will disappear and there will be no tendency to injure the tie, as often occurs 85 when pressing with hot irons.

To facilitate removal of the device from the tie, the inner edges of the form sections 7 may be formed with opposed notches 17 through which one or more of the user's fin-gers may be inserted.

I claim:—

1. A necktie stretcher comprising two flat longitudinally tapered form sections connect-ed with each other at their narrow ends, a coiled compression spring interposed between 95 the wide ends of said sections and exerting its force to spread the same, a channel-shaped clip receiving said spring and said wide ends of said form sections, and means slidably con-necting said sections with said clip.

2. A necktie stretcher comprising two flat longitudinally tapered form sections connected with each other at their narrow ends, a coiled compression spring interposed between the wide ends of said sections and exerting its force to spread the same, the diameter of said spring being greater than the thickness of said form sections; a clip receiving said spring and said wide ends of the form sections, said clip comprising a plate bent substantially upon itself and shaped to provide a tubular bead receiving said spring, and two parallel wings projecting from said bead and lying slidably against opposite sides of said form sections, and fasteners passing through said wings and the intervening form sections, the latter having slots through which said fasteners extend.

In testimony whereof I affix my signature.

JULIUS H. WEIN.
